S. OAKMAN.
GLASS FURNACE.

No. 88,066.

Patented Mar. 23, 1869

INVENTOR:
Samuel Oakman

SAMUEL OAKMAN, OF BOSTON, MASSACHUSETTS.

Letters Patent No. 88,066, dated March 23, 1869.

IMPROVED GLASS-FURNACE.

The Schedule referred to in these Letters Patent and making part of the same.

To all whom it may concern:

Be it known that I, SAMUEL OAKMAN, of Boston, in the county of Suffolk, and State of Massachusetts, have invented certain new and useful Improvements in Glass-Furnaces; and I do hereby declare that the following is a full and exact description thereof, reference being had to the accompanying drawings, and to the letters of reference marked thereon.

The nature of my invention consists in combining, with a glass-furnace, a vacuum-chamber, in which the exhaust is produced by mechanical means, said chamber being connected to the furnace by suitable flues, so that a proper draught may be maintained. This vacuum-chamber has inlets over the ports of the furnace, so that the flame and heated products of combustion coming from the ports may be drawn into the vacuum-chamber, and thus away from the workmen.

The object of the invention is to secure a more perfect draught and ventilation, also saving the expense of large chimneys.

To enable others skilled in the art to make and use my invention, I will proceed to describe its construction and use.

In the drawings—

Figure 1 is a perspective view of the furnace.

Figure 2 is a longitudinal vertical section through the centre.

Figure 3 is a longitudinal vertical section passing through the two side chimneys H.

Figure 4 is a cross-vertical section of a part.

My furnace is constructed of brick, or any suitable material, and provided with two fire-boxes, B and B', one at each end, and a channel, B'', connecting the two, through which the flame passes into the chamber S, in which the melting-pots are placed.

For convenience in placing the pots, and also to obtain the best results from the fire, benches, one of which is shown at T, fig. 4, are made at each side of the fire-channel B'', running the whole length of the furnace.

On the level with these benches, or sieges, large openings or foot-holes, C C' C'', are made, for convenience in mending the pots and sieges.

D D D are small working-holes immediately over the foot-holes, through which the glass is drawn for use.

Each one of the small openings, or working-holes, D D D, is provided with a cover, P, fig. 1, and also with an outside slide, N, one of which is shown in figs. 1 and 4.

Immediately above each of the openings, or working-holes, D D D, an orifice is made leading into the

vacuum-chamber, one of which, R, is shown in fig. 4, so that when desirable, the slide N may be closed, as shown in fig. 4, and a communication be made with the fire-chamber T and the vacuum-chamber V.

Each of the openings R, into the vacuum-chamber, is provided with sliding doors, so they may be closed, if desirable.

At each corner of the furnace, a flue, h H h', is constructed, which serves to lead the products of combustion from the chamber S to the vacuum-chamber V. (See fig. 3.)

K, figs. 1, 3, and 4, is an exhaust-fan, which is connected with the vacuum-chamber, by the pipe h, and which serves to draw the gases from the vacuum-chamber, and discharge them through the pipes L and M.

These gases may be discharged directly out of doors, or, if they are to any degree combustible, they may be sent, wholly or in part, back into the fire through the pipe L' M'; the pipes L L', M M' being provided with suitable dampers, so that the gases flowing through them may be directed back to the fire, or out of doors.

While the glass is being heated, the working-holes D D D are closed, so that no air is admitted to the furnace, except that which comes from the blast, but when the glass is being worked, the slides N are raised, the working-holes are opened, and the orifices R, opening into the vacuum-chamber, are also open, so that there will be a strong draught, or current of air passing immediately in front and over the working-holes into the vacuum-chamber.

This draught will carry all the flame and smoke that escapes from the working-holes up into the vacuum-chamber, and also furnish fresh air for the workmen, thus enabling them to work with much more ease and comfort.

In the drawings, I have represented a common fan-blower as the exhaust-device, but I do not wish to confine myself to this alone, as there are other well-known machines for exhausting air, which would work equally well in combination with my vacuum-chamber.

What I claim as my invention, and desire to secure by Letters Patent of the United States, is—

Combining, with a glass-furnace, a vacuum-chamber, V, arranged with openings and flues, substantially as described, when the same is provided with mechanical exhaust-device, working substantially as described and for the purpose set forth.

SAMUEL OAKMAN.
